UNITED STATES PATENT OFFICE.

GEORGE WASHINGTON TURTON, OF ALMA, WISCONSIN.

FLY-TRAP.

SPECIFICATION forming part of Letters Patent No. 664,449, dated December 25, 1900.

Application filed October 26, 1900. Serial No. 34,487. (No model.)

To all whom it may concern:

Be it known that I, GEORGE WASHINGTON TURTON, a citizen of the United States, residing at Alma, in the county of Buffalo and 5 State of Wisconsin, have invented a new and useful Fly-Trap, of which the following is a specification.

This invention relates to fly-traps in general, and more particularly to that class 10 wherein the fly-receiver is held stationary and the bait-carrier is moved to carry the flies into position below the receiver, the flies being then frightened, so that they will rise into the receiver.

One object of the invention is to provide a 15 simple and efficient construction wherein the flies will not clog the apparatus and prevent its operation and wherein the retainer may be readily moved into and out of operative 20 position.

A further object of the invention is to provide a support for the retainer to which the retainer may be easily applied and from which it may be readily removed, further objects 25 and advantages of the invention being evident from the following description.

In the drawings forming a portion of this 30 specification, and in which like numerals of reference indicate similar parts in the several views, Figure 1 is a perspective view showing the complete trap. Fig. 2 is a section through the receiver in a plane passing diametrically through the bait-carrier. Fig. 3 is a section through the receiver in a plane 35 at right angles to the plane of Fig. 2. Fig. 4 is a section on line 4-4 of Fig. 2.

Referring now to the drawings, 5 represents a hollow base, within which is located a motor of any suitable form, and preferably a spring- 40 motor, this motor including a spindle 6, which projects through the top of the base and on which is fixed a disk-shaped bait-carrier 7, which is centrally mounted and in the upper face of which is formed an annular groove or 45 channel 8 concentric with the disk, which latter is disposed to rotate in a horizontal plane. As will be understood, the groove 8 receives the bait in whatever form it may be, but which should be of some substance that will 50 not tend to entrap the flies, as does what is commonly known as "fly-paper," so that the

flies may readily leave the carrier at the proper time.

Attached to the side of the base 5 is an outwardly and upwardly extending arm 10, the upper end of which lies horizontal in a plane above the plane of the bait-carrier, and this extreme end portion has a vertical perforation 11 therein, and in the rear of this perforation is formed a slight depression or groove 12, which opens through one side face thereof in a direction opposite to the direction of rotation of the bait-carrier. A support for the fly-receiver consists of an arm 13, having a perforation in its extremity for alignment with the perforation of the arm 10 to receive a pivot-bolt 14, and at the opposite end of the arm 13 is formed an annular loop 15, which is adapted to lie above the bait-carrier and with its center over the groove therein. The supporting-arm is adapted for movement into and out of position over the bait-carrier because of its pivotal mounting, but may be moved from its operative position in one direction only, which is opposite to the direction of rotation of the carrier, the object of this arrangement being to prevent accidental displacement of the arm 13 should it from any cause become connected with the carrier.

The fly-receiver consists of a preferably foraminous body portion 16, having an annular open bottom, and in this bottom is fitted a cone 17, also of foraminous material, having an aperture at its upper end opening into the body portion of the receptacle, this structure being in common use and well known. From the lower edge of the body portion of the receptacle there depends an imperforate metallic flange 18, which extends only part way around the open end of the receptacle, the interspace 19 between the ends of this flange forming a gate for access to the inclosure of the flange. When the receiver is in place, it rests in the loop of the arm 13, with the lower edge of the flange 18 parallel with and spaced slightly above the bait-carrier, as shown.

In practice the flies alight upon the bait-carrier and feed at the groove therein, the rotation of the carrier by its motor carrying the flies through the gate or interspace 19 and into the inclosure of the flange. Ordinarily the flies would be brought into bodily contact

with the flange 18 and would be likely to have their feet caught between the flange and the bait-carrier and ultimately to become wedged in between the flange and carrier, so as to prevent rotation of the carrier, it being understood that the flange must be spaced slightly above the carrier to permit the latter to rotate. To prevent this contact of the flies with the flange, a scraper 20 is provided, and consists of a plate of metal which is preferably curved, as shown in Fig. 3, the rear upper edge of the plate being bent to form a tubular sleeve, which is pivotally engaged with a pintle 21, secured to the flange 18. The plate 15 of which the scraper is formed extends downwardly and slantingly in a direction opposite to the direction of rotation of the bait-carrier, and the lower edge of the plate is arched, so that only the ends of the lower edge rest upon 20 the surface of the bait-carrier, this arch extending over the groove in the carrier. Thus as the carrier moves the flies they are brought into contact with the scraper, which lies flat against the carrier only at the tips of its lower edge, while the intermediate portion of the lower edge is cut away, so as not to permit of 25 catching a fly.

It will be understood that in practice various modifications of the specific construction 30 may be made and that any suitable materials and proportions may be used for the various parts without departing from the spirit of the invention.

What is claimed is—

- 35 1. A fly-trap comprising a rotatable bait-carrier, a fly-receiver comprising a body portion having a depending flange of lesser diameter than the body of the receiver and having a gate through the flange leading to the inclosure thereof, and a supporting-arm having a loop disposed to receive the flange and support the body of the receiver with the flange in close proximity to the bait-carrier.
- 40 2. A fly-trap comprising a movable bait-carrier having a groove therein to receive bait, a fly-receiver comprising a body portion having a depending flange provided with a

gate leading to the inclosure of the flange, and a movable arm having a loop adapted to receive and support the fly-receiver with the flange thereof in close proximity to the bait-carrier and with the gate in registration with the groove of the carrier.

3. A fly-trap comprising a movable bait-carrier having a bait-receiving groove therein, and a fly-receiver comprising a body portion supported above the carrier and having a depending flange lying in close relation to the carrier, said flange having a gate leading to the inclosure of the flange and registering with the groove, and a pivoted scraper-plate disposed downwardly and forwardly in a direction against the movement of the bait-carrier, the lower edge of the scraper-plate being arched and lying with the ends of the arch against the bait-carrier.

4. A fly-trap comprising a rotatable annular bait-carrier a fixed arm having a slot formed part way across it, a supporting-arm pivoted to the extremity of the first arm and having a lug for engagement with the slot to permit movement in one direction only from a position alining with the first arm, the supporting-arm having a loop at its opposite end adapted to lie above the bait-carrier when 75 said arm is alined with the first arm, and a fly-receiver comprising a body portion supported removably in the loop and having a flange depending therefrom and lying in close proximity to the carrier, said flange having 80 an entering-gate therein, and a pivoted scraper connected with the upper portion of the flange and extending downwardly and in the direction of the gate, the lower edge of the scraper being arched and having the ends 85 of the arch resting slidably on the carrier.

In testimony that I claim the foregoing as my own I have hereto affixed my signature in the presence of two witnesses.

GEORGE WASHINGTON TURTON.
